UNITED STATES PATENT OFFICE.

GEORGE F. GIESECKE, OF LEIPSIC, GERMANY, ASSIGNOR TO JAMES CONNER'S SONS, OF NEW YORK, N. Y.

DESIGN FOR TYPE.

SPECIFICATION forming part of Design No. 16,341, dated October 20, 1885.

Application filed September 1, 1885. Serial No. 175,939. Term of patent 7 years.

To all whom it may concern:

Be it known that I, GEORGE F. GIESECKE, of Leipsic, Kingdom of Saxony, Empire of United Germany, (assignor to JAMES CONNER'S SONS, of the city, county, and State of New York,) have invented and produced a new Design for a Font of Printing-Type, of which the following is a specification.

The nature of my design is clearly shown in the accompanying typographic impression, to which reference is made; and it consists of an unshaded text letter of the Gothic period, and of condensed character.

The A, B, D, F, H, I, J, K, L, M, N, P, R, U, Y, and Z are ornamented upon the left about centrally by the square ornaments placed transversely. In the Z they are a part of the up-and-down line. In the other letters they are placed beyond and outside of the up-and down portion. The faces of the A, F, N, P, and Y are ornamented by the light vertical line with dot termination. The B, C, E, F, G, H, K, L, M, O, Q, R, and S are ornamented above, upon the left, by the light curved line flourishes. The A, D, I, J, N, P, T, U, V, W, X, and Z are ornamented by the heavy flourishes curving to the left and downward, and placed above the letters. The A, E, F, M, N, O, P, Q, X, and Y are further ornamented by the heavy parallel lines, as shown. The B, D, and Z are further ornamented by the light lines, as shown. In the H and U the heavy inclined lines ornament the faces of the letters, as shown. The upper right-hand termination of the S consists of a square figure placed transversely, followed by the light line curling to the right. The upper right-hand termination

of the T consists of the light curved line with dot termination.

The character of the design is preserved in the numerals, save that the flourishes and ornamentation of the faces are omitted.

Having now set forth my invention, I claim as new—

A design for a font of printing-type, as herein described and shown, consisting of a condensed text letter of the Gothic period, ornamented, as in the A, B, D, F, H, I, J, K, L, M, N, P, R, U, Y, and Z, upon the left about centrally by the squares placed transversely; the faces of the A, F, N, P, and Y ornamented by the light vertical lines with dot termination; the B, C, E, F, G, H, K, L, M, O, Q, R, and S ornamented above upon the left by the light curved-line flourishes; the A, D, I, J, N, P, T, U, V, W, X, and Y ornamented upon the left, by the heavy flourishes; the A, E, F, M, N, O, P, Q, X, and Y ornamented by the heavy parallel lines, as shown; the B, D, and Z ornamented by the light lines, as shown; the H and U ornamented by the heavy inclined lines, as shown; the upper termination of the S upon the right consisting of the square placed transversely, followed by a light line curling to the right, and the T having its upper right-hand termination formed of a light curved line with dot termination, and a series of numerals from 1 to 0, inclusive, in which the flourishes and facial ornamentation are omitted.

GEORGE F. GIESECKE.

In presence of—

JOHN K. TETLOW,
C. BORNGRAEBER.
